(57) **CLAIM**

I claim the ornamental design for an automobile tire, as shown and described.

DESCRIPTION

FIG. 1 is a perspective view of an automobile tire showing my design;

FIG. 2 is a front view thereof;

FIG. 3 is a rear view thereof;

FIG. 4 is a left side view thereof;

FIG. 5 is a right side view thereof;

FIG. 6 is a fragmentary enlarged front view surrounded by line A-A and line B-B in FIG.2 thereof;

FIG. 7 is a section view taken along line C-C in FIG.6 thereof; and,

FIG. 8 is a reference view.

In FIG. 8, the solid contrast is for the purpose of highlighting the grooves. The black contrast is for the purpose of highlighting the deepest grooves, and the gray contrast is for the purpose of highlighting the less deep grooves.

The broken lines are for the purpose of showing environmental structure only and form no part of the claimed design.
